TAPE APPLYING MACHINE

Edward F. Small, Newton, Mass., assignor to Prime Manufacturing Company, Lynn, Mass., a corporation of Massachusetts

Filed Jan. 27, 1959, Ser. No. 789,377
10 Claims. (Cl. 12—59.5)

This invention comprises a new and improved machine for applying adhesive tape to parts of shoe uppers and is characterized by means for automatically setting the operating instrumentalities of the machine for action by the presentation of the work thereto.

Machines of this type have heretofore included a treadle or manual devices which must be depressed or moved by the operator in order to open guides for the work, space feeding devices, or make other preliminary settings of the machine parts. In accordance with the present invention all such devices are eliminated and instead means are provided for initially holding the instrumentalities of the machine in inoperative positions, in combination with a trigger operated by presentation of the work to the machine and connections for moving the instrumentalities into operative relation with the work and the tape.

For example, the machine here shown comprises a rotary work support, a cooperating presser member and a tape-cutting knife together with means for initially holding the presser member and knife in inoperative positions and also a trigger located so that it is naturally engaged by the work as it is presented to the rotary support and connected mechanism for moving the presser member and knife into operative positions. This not only facilitates the work of the operator but improves the accuracy of the operation and eliminates false starts and incidental damage that have been serious obstacles and the cause of considerable loss to manufacturers relying upon older types of tape laying machines.

These and other features of the invention will be best understood and appreciated from the following description of a preferred embodiment thereof, selected for purposes of illustration and shown in the accompanying drawings, in which:

FIG. 1 is a view of the machine in side elevation with its parts in working positions,

FIG. 2 is a similar view showing the parts of the machine in their initial inoperative positions,

FIG. 3 is a fragmentary view of the machine in front elevation,

FIG. 4 is a detailed view of the driving gear system,

FIG. 5 is a view in perspective of the tape cutting knife shown on an enlarged scale,

FIG. 6 is a view in elevation of parts shown in FIGS. 1 and 2 with the spider omitted,

FIG. 7 is a fragmentary front view of the parts shown in FIG. 6, and

FIG. 8 is a fragmentary view, partly in elevation and partly in section on the line 8—8 of FIG. 7.

The frame of the machine takes the form of a hollow column or casing 10 to which is secured a forked bracket 11 in the upper end of which is mounted a work supporting roll 12 upon a transverse shaft 13. The roll 12 as shown in FIG. 3 has a central circumferential section of reduced diameter in which is located a stationary horn 14 having an angled or bevelled periphery which acts as a seam guide when the work comprises the back seam of an upper. In dealing with such work the horn 14 runs in the crease of the back seam of the upper while the adjacent margins of the counter are flattened and covered by a length of adhesive tape. The horn is shown as secured to a lug projecting from the bracket 11.

2

Also mounted in the bracket 11 is a trigger 15. This is arranged to swing about a pivot 16 and has an inwardly projecting ear which engages the operating button of a microswitch 17. The trigger 15 as shown in FIG. 3 has at its upper end a wide pad which, in the initial position of the trigger is located a short distance from the circumference of the work supporting roll 12. The spring of the operating button of the switch holds the trigger in this position as shown in FIG. 2 and the trigger is so located that it is engaged by presentation of the work W to the roll 12 and caused to move in an anti-clockwise direction from the position shown in FIG. 2 to the position shown in FIG. 1. In this movement the trigger opens an electric circuit through the microswitch 17 with results which will be presently described. The operator usually presents the work to the machine by holding it with both hands, one on each side of the back seam and of the trigger 15.

A large feed roll 20 is rotatably mounted upon a shaft 21 in cooperative feeding relation to the work supporting roll 12. The shaft 21 is rotated clockwise through several reducing gears from a small gear upon the shaft 22 as shown in FIG. 4. The shaft 22 carries a driving pulley at its outer end not shown and a hand wheel 23. The main shaft 22 operates a second gear train 24, 25 secured to a small shaft continuously driving a small feed wheel 26 which as shown in FIGS. 1 and 2 cooperates with the work supporting roll 12 to engage and advance the work W and the tape T when these elements are introduced between the roll 12 and the small feed roll 26.

A shaft 30 is mounted on top of the machine casing 10 and upon this is mounted a spider 32 biased always to rock in a clockwise direction by a torsion spring 31 which encircles the shaft 30. The operation of the spring 31 is to hold the machine parts in their operative position shown in FIG. 1. The spider has an arm extending toward the left as shown in FIGS. 1 and 2 and to the outer end of this arm is connected a link 33 which is pivotally connected at its lower end to the plunger 34 of a solenoid 35 fast to the rear side of the casing 10. Electrical connections 36 run from the solenoid 35 to the microswitch 17 with the result that when the trigger 15 is rocked toward the work supporting roll 12 in the presentation of the work the switch 17 is open, the solenoid 35 de-energized and the machine parts are held in their operative positions as shown in FIG. 1 by the action of the spring 31.

The spider is provided with an upwardly extending arm 37 which engages an adjustable stop 38 and thus limits the clockwise spring activated movement into operative position of the spider and its connected parts. The spider has also a forwardly extending arm 46 carrying a pivot pin 42 upon which is mounted a rocker 41 of bell crank shape. The shaft 30 in addition to the spider carries an upstanding arm 43 upon which is mounted a spring 44 tending at all times to swing the rocker 41 in a clockwise direction. A downwardly extending arm 45 is pivotally mounted at its upper end upon an ear projecting from the machine frame, as best shown in FIG. 6. A cam follower roll 46 is operated by a cam 47 mounted to oscillate upon the shaft 21. The spider 32 has an arm 48 carrying at its lower end a roll which is engaged in a slot 49 in the cam 47. In FIG. 2 the spider is shown as being rocked into its extreme left hand or inoperative position by the action of the solenoid thereby oscillating the cam 47 so that its highest point engages the follower roll 46 and swings the rocker 41 outwardly. The rocker 41, with all the parts mounted thereon, may be swung approximately 90° in an anti-clockwise direction about the pivot 42 and will be held by the spring 44 in that position to provide convenient access to the feed roll 26 in threading the tape there-

to. In other words, the spring 44 is adapted to hold the rocker 41 in either of two positions on the arm 40 viz. that shown in FIGS. 1 and 2 or an outer position opening the elements of the machine for inspection, cleaning, etc.

The cam follower roll 46 is mounted upon an arm located behind the arm 45 and which is a part of the assembly mounted to rock about the pivot 42 including the block 53 referred to hereinafter.

The machine is equipped with a forked presser or work guide 50 which cooperates with the work supporting roll 12 in holding and guiding the work as it is introduced into the machine. This guide comprises two diverging sheet metal leaves as shown in FIG. 3 which are secured in position by a clamping plate 51 against a carrier plate 52. The carrier plate 52 is secured in a block 53 by a holding pin 54 which is engaged by a latch plunger 55 movably mounted in the block. By depressing the plunger 55 the holding pin 54 is released and may be withdrawn for temporary detachment of the forked work guide 50. The block 53 is rigidly attached to the lower arm of the bell crank rocker 41; accordingly, when the spider is swung by the spring 31 to the limit stop 38 the presser guide 50 is held in operative position on the work by pressure of the spring 44 upon the rocker 41 backed by the holding pressure of the spring 31 on the spider which yieldingly prevents the guide from relaxing its engagement with the work.

A tape severing knife 56, best shown in FIG. 5, is mounted upon a shaft 57 journaled in an ear projecting from the cam 47. At its rear end the shaft 57 carries a forked link 58 which is in turn pivotally connected to the lower end of the link 45. When the cam 47 is moved to its right hand position as shown in FIG. 2 the knife 56 is rocked forwardly to sever the tape. When the cam is moved in the other direction to the position shown in FIG. 1 the action of the cam and the link 58 rock the knife 56 out of the path of the tape as indicated in FIG. 1. The tape as best shown in FIG. 1 is led to the machine between guide rolls journaled in the upper end of an arm 62 projecting upwardly from the rear side of the machine frame. From these rolls the tape passes through a wire guide 63 between guide rolls 64 and downwardly through a flat tape guide 39.

The machine includes automatic means for advancing the tape to the bite of the feed roll 26 when the trigger 15 is tripped and the presser 50 brought into its operative position. To this end a rocker plate 70 is pivotally mounted to swing about the axis of a pin 71 in the top of the machine frame. At its free end the rocker 70 carries an intermittently oscillated feed wheel 72 over which the tape passes. This feed wheel is oscillated forwardly through connections with a horizontal link 73 which is activated by the arm 48. An adjusting arm 74 connected to the rocker 70 through a curved slot permits adjustment regulating the throw of the feed wheel 72 by moving the point of connection of the arm 72 nearer to or further from the axis of the rocker 70. A clamping plate 75 carried by an arm 76 is arranged to engage the tape for feeding it and to hold it against retrogression. The arm 76 is mounted on a pivot projecting transversely from the rocker 70 and is urged downwardly by a vertical tension spring 70' as shown in FIG. 6. It is lifted by a drop-off cam 72' on the shaft of the roll 72 and when released by this cam the plate 75 engages the tape passing over the top of the roll 72 in the proper time and relation causing the tape to advance when the roll is oscillated. It will be apparent therefore that when the trigger 15 is tripped and the spider oscillated to bring the forked presser into operative position the tape feeding mechanism above described will advance the previously severed end of the tape so that it will be engaged between the feed roll 26 and the work which is being introduced upon the work-supporting roll 12. The arm 48

extends upwardly from the shaft 30 and is pivotally connected at its upper end to the link 73.

In operation the advancing edge of the work trips the trigger, thus causing the instrumentalities of the machine 5 to move into their operative position and holding them there so long as the work engages the trigger. At the instant when the trailing edge of the work passes beyond the trigger the latter swings outwardly closing the microswitch 17, energizing the solenoid 35 and causing all parts 10 of the machine to reassume their initial positions.

Having thus disclosed my invention and described in detail an illustrative embodiment thereof I claim as new and desire to secure by Letters Patent:

1. A machine for laying tape comprising a work support, a forked overhead guide initially spaced above the support, a trigger located in advance of the support, and mechanism tripped by movement of the trigger when contacted by the work for automatically lowering the forked guide into contact with the work.
2. A machine for laying reinforcing tape, comprising a rotary work support, an overhead guide initially spaced from the support and movable into guiding contact with work thereon, a trigger located in advance of the support and in position to be engaged by work presented there- 25 to, spring means tending to move the overhead guide into operative position, a solenoid connected with the guide and maintaining it normally in its overhead position, and connections operated by the trigger for de-energizing the solenoid upon the presentation of the work.
3. A machine for laying adhesive tape comprising a work-supporting roll, and a cooperating pivotally mounted presser member, a spider to which said presser member is connected, a spring tending to rock the spider and presser member in one direction, and a solenoid energized 30 to rock the spider and presser member in the other direction.
4. A machine for laying adhesive tape as described in claim 3, further characterized by a trigger pivotally mounted adjacent to the work-supporting roll in position 35 to be tripped by the work as presented to said roll, an electric switch operated by the trigger, and electric connections between the switch and the solenoid.
5. A machine for laying adhesive tape as described in claim 3, further characterized by an oscillating tape-cutting knife, and operating mechanism therefor controlled by the release of said trigger by the work.
6. A machine for laying adhesive tape as described in claim 5, further characterized by a cam oscillated by 45 said spider, and operative connections between the cam on the one hand and both the pressure member and knife on the other hand for moving said presser member and knife simultaneously.
7. A machine for applying tape to shoe parts and the like, comprising a rotary work support, a cooperating presser member, and a tape-cutting knife, means for initially holding the presser member and knife in inoperative positions, a trigger operated by presentation of the work to the work support and connected mechanism for moving said presser member and knife into operative positions.
8. A machine for laying adhesive tape on parts of shoe uppers, comprising a rotary work support, an overhead guide initially spaced above the support, a trigger located adjacent to the support, tape feeding means, and mechanism controlled by the trigger for simultaneously lowering the guide into contact with work on the support and actuating the tape feeding means.
9. A machine for laying adhesive tape on parts of shoe uppers and the like, comprising a work supporting roll, a cooperating feed roll, an oscillatory spider pivotally mounted above said feed roll and having arms extending in opposite directions from its axis of oscillation, a solenoid connected to one of said arms, a work guide cooperating with the work supporting roll and con- 70 75

trollably connected to the other of said arms, and a spring acting on the spider in opposition to the solenoid.

10. A machine for laying adhesive tape on shoe parts and the like, comprising a work-supporting roll, a co-operating feed roll, and a cam mounted for oscillation about the axis of the feed roll, a spider mounted to rock on an axis above the cam and having operating connections therewith, a trigger-controlled solenoid connected to the spider for rocking it in one direction and a spring for rocking it in the opposite direction, together with a 10 work guide movable toward and from the work-support-

ing roll through the medium of the spider in accordance with the oscillation of said cam.
